(57) **CLAIM**

The ornamental design for a leaflet holder, as shown and described.

DESCRIPTION

FIG. 1 is a front perspective view of a leaflet holder showing the new design;

FIG. 2 is a right, side elevational view of the leaflet holder shown in FIG. 1 (the left, side elevational view of the leaflet holder is a mirror image of the view shown in FIG. 2);

FIG. 3 is a top view of the leaflet holder shown in FIG. 1; FIG. 4 is a front elevational view of the leaflet holder shown in FIG. 1, the rear surface being devoid of surface ornamentation; and,

FIG. 5 is an inverted bottom view of the leaflet holder shown in FIG. 1.
